WASHING MACHINE

Lewis A. James, Independence, Kans.

Application June 8, 1936, Serial No. 84,115

5 Claims. (Cl. 74—78)

This invention relates to washing machines particularly those of the power driven type and has for its principal object to provide a simple and relatively inexpensive driving connection of the prime mover with the agitating mechanism of the machine.

Other important objects of the invention are to provide a clutch mechanism that may be readily operated to connect and disconnect the power from the agitator; to provide for adequate lubrication of the working parts by means of a common oil bath in which the parts operate; and to provide manual means for selectively operating the washer in case of failure of the power supply or the prime mover.

In accomplishing these and other objects of the invention, I have provided improved details of structure, the preferred form of which is illustrated in the accompanying drawings, wherein:

Fig. 1 is a perspective view of a washing machine embodying the features of the present invention, a portion of the tub being broken away to illustrate the agitator mechanism.

Fig. 2 is an enlarged detail vertical section through the transmission mechanism.

Fig. 3 is a cross-section on the line 3—3 of Fig. 6.

Fig. 4 is a similar cross-section on the line 4—4 of Fig. 2.

Fig. 5 is a horizontal section through a side wall of the washing machine showing the transmission housing in plan with a portion of the cover broken away to better illustrate the operating mechanism and showing the clutch connection in engaged position.

Fig. 6 is a similar view showing the clutch connection in disengaged position.

Fig. 7 is a detail perspective view of the pitman.

Fig. 8 is a detail perspective view of the rack and its pin which is engageable by the pitman.

Fig. 9 is a perspective view of the pitman control parts.

Fig. 10 is a perspective view of the crank for manually operating the washing machine.

Referring more in detail to the drawings:

I designates a washing machine embodying the features of the present invention and which includes a tub 2, an agitator 3 that is oscillatably mounted in the tub, a prime mover 4, a wringer 5, and a transmission 6 selectively connecting the prime mover with the agitator 3 and a wringer 5. The tub 2 has a substantially semi-cylindrical bottom 7 connected by end walls 8—9 and side walls 10—11 to form an agitating chamber 12 having an open top 13 through which clothes are

inserted into the washer, the open top being covered by a suitable lid 14. The upper edge of the tub is reinforced by a framework 15 that is supported at its corners on legs 16 to space the tub from the floor and provide a compartment 17 thereunder for housing the prime mover 4.

In the illustrated instance the prime mover 4 is shown as an electric motor having its base 18 fixed to a cross bar 19 extending between a pair of adjacent legs 16. In order to enhance the appearance of the tub the spaces between the respective legs are closed by suitable panels 20.

The agitator 3 includes spaced arms 21 and 22 operable in close proximity to the inner sides of 15 the end walls and which have their upper ends oscillatably mounted in the axis of the semi-cylindrical bottom 7 so that an agitating blade 23 carried at the outer ends of the arms, moves in an arc across the bottom of the tub. The pivot 20 member for the arm 22 may constitute a suitable trunnion (not shown), but the pivot member for the arm 21 comprises a shaft 24 that forms a part of the transmission 6, now to be described.

The transmission 6 includes a housing 25 having spaced side walls 26 and 27 preferably connected by end walls 28 and 29 and a bottom 30 to provide a compartment 31 for containing the operating mechanism, the top of the compartment being closed by a removable cover plate 32 having its side edges overlapping the side and end walls and secured thereto by suitable fastening devices, such as screws 33, extending through suitable openings in the cover and into threaded sockets 34 formed in the side walls.

Carried by the side walls 26 and 27 and bottom 30 are spaced bearing bosses 35 and 36 having bushed openings 37 and 38 to rotatably mount the shaft 24. The outer ends of the bushed openings are counterbored, as at 39 and 40, to accommodate packing elements 41 and 42 to form a seal about the shaft and prevent escape of lubricant from the transmission housing. The packing elements are retained in the counterbores 39 and 40 by plugs 45 and 46 that are threaded into the side walls 26 and 27 and which have openings 47 and 48 to accommodate the shaft. The plug 46 has an annular flange 49 to cooperate with the side wall 27 for clampingly engaging the end wall of the tub to seal the opening 50 therein through which the shaft 24 is extended. The inner end 51 of the shaft projects within the agitating chamber a sufficient distance to mount the agitator arm 21 which is keyed thereto by a pin or the like 52. The opposite end of 55

the shaft projects through the plug 45 and into a tubular boss 53 projecting from the side 26 of the transmission housing to form a bearing for the socket 54 of a hand crank 55 that is connectable with the shaft in case of failure of the prime mover or its power supply, as later described. The socket 54 is provided with notches 57 and 58 to engage the ends of a pin 59 extended through the shaft. When the hand crank is not in use the open end of the tubular boss may be closed by a suitable cap (not shown).

Fixed on the shaft between the bearing bosses by a spline 60 is a pinion gear 61 having its teeth 62 meshing with the teeth 63 of a rack bar 64 provided with grooved ways 65 and 66 slidably engaging guide ribs 67 and 68 of a guide block 69. The guide block 69 is bolted in position in the transmission housing by suitable fastening devices, such as cap screws 70, extending through openings 71 in the bottom of the case and having threaded shanks 72 engaging in threaded bores 73 of the block as best shown in Fig. 2. The under side of the block is recessed, as at 74, to cooperate with an arcuate depression 75 in the housing to accommodate the pinion gear. The guide ribs extend inwardly from the side walls 76 and 77 of a groove 78 extending longitudinally of the block. The block is of sufficient width to provide sliding support for a pitman 79, later described.

Located in the opposite end of the transmission housing and formed on the cover plate 32 and bottom 30 respectively are vertically arranged bearing bosses 80 and 81 having bushed openings 82 and 83 for rotatably mounting the shaft sections 84 and 85 of a crank-shaft 86, the shaft sections having crank arms 87 rotatable in the upper portion of the transmission housing and connected by a crank-pin 88 on which the pitman is pivotally mounted.

The shaft section 85 of the crank-shaft carries a worm gear 89 that meshes with a worm 90 fixed to a power shaft 91 extending transversely of the housing in parallel relation with the agitator shaft 24. The shaft 91 has its ends mounted in bushed bearings 92 and 93 formed in the side walls of the housing as best shown in Fig. 3. The bearing opening in the outer side wall 26 is closed by a threaded plug 94 but the bearing opening in the opposite side wall is counter-bored to contain a sealing element 95 to prevent escape of lubricant about the projecting end of the worm shaft 91. The packing element is retained in position by a threaded plug 96 similar to the threaded plugs on the agitator shaft, previously described.

Fixed to the projecting end of the worm shaft is a grooved pulley 97 that is aligned with a similar pulley 98 on the power shaft of the prime mover 4, the pulleys being operably connected by a belt 99 running in the grooves of the respective pulleys. In order to accommodate the pulley 98 the side wall 26 of the transmission housing is inset as at 100.

The bearing boss 81 of the cover plate projects above the top of the tub and rotatably mounts the wringer 5 as in conventional practice. The shaft section 84 of the crank-shaft forms an actuating shaft for operating the rolls of the wringer, the specific form of connection between the shaft and the wringer 5 forming no part of the present invention.

The clutch pitman 79 constitutes an important part of the present invention and includes a bar 101 having an opening 102 in one end thereof to

form a bearing through which the crank-pin of the crank-shaft is extended. The opposite end of the pitman extends over the upper surface of the guide block and is provided with a hook-shaped head 103 having a notch 104 opening from a side thereof to engage a pin 105 projecting upwardly from the rack bar 64. The forward end of the pitman is inclined from the outer end thereof toward the notch 104 to form a cam surface 106 to guide the head into coupling engagement with the pin 105. The upper face of the pitman is provided with a longitudinal guide groove 107 terminating at the inner end thereof in an arcuate oil passage 108 wherein oil is collected incidental to rotation of the crank and delivered to the longitudinal groove to lubricate a guide pin 109 that retains the pitman in or out of engagement with the pin 105 of the rack. In order to manually move the pitman into engagement or disengagement with the pin 105, the guide pin 109 is carried on a lever 110 fixed to a shaft 111 that is rotatably mounted in a bearing 112 of the cover plate and which has an operating knob 113.

Loosely mounted on the guide pin between the lever 110 and the pitman is a plate 114 having its free end 115 connected by a coil spring 116 with an anchor 117 to retain the guide pin supporting lever in one or the other of its two positions, the anchor for the spring being located substantially midway of the two positions so that when the guide pin is moved across dead center relatively thereto the spring will continue movement of the lever until it has engaged a stop pin 118 or 119 on the cover.

The transmission housing thus described is supported on the end of the tub by fastening devices such as cap screws 123, shown in Figs. 2 and 5.

In using a machine constructed and assembled as described, and assuming that the pitman is disengaged from the pin 105 of the rack bar, the wash fluid and clothes to be washed are inserted in the tub and the motor started to drive the worm shaft 91 through the belt and pulley connection. Rotation of the worm shaft 91 causes the worm 90 to drive the worm gear 89 on the crank-shaft and effect rotation thereof. Rotation of the crank-shaft causes the pitman 79 to reciprocate over the upper face of the guide block in guided relation with the guide pin 109 which operates in the groove 107 and normally retains the clutch pawl from engagement with the pin 105. When in this position, the arm carrying the guide pin engages the stop pin 119 and is held thereagainst by action of the spring 116. The agitator is now set in operation by rotating the knob 113 in a counterclockwise direction toward the other stop 118. When in this position the cam face 106 on the pitman head engages the pin 105 so that the pitman reciprocates thereagainst until the notch 104 registers with the pin 105 whereupon the spring 116 will continue movement of the lever 110 carrying the guide pin 109 into engagement with the other stop 118, causing the notch 104 to engage over the pin 105, thereby connecting the rack bar in driving relation with the pitman.

Reciprocation of the pitman now produces reciprocation of the rack bar 64 to effect oscillation of the pinion gear 61 which in turn oscillates the agitator mechanism back and forth over the bottom of the tub to wash the clothes. When the pitman is to be disengaged from the rack 64, the knob 113 is rotated in the opposite direction, past dead center position, whereupon the spring is 75

again effective to draw the lever arm 110 against the stop pin 118, and since the guide pin 109 is still engaged in the guide groove 107 of the pitman, the pitman will reciprocate on the upper face of the guide block 69 during continued rotation of the crank-shaft. As soon as the notch 104 is disengaged from the pin 105 the rack bar will have stopped its reciprocation to suspend operation of the agitator mechanism.

10 In case of failure of the power, the cap closing the tubular boss may be removed and the hand crank 55 applied to the projecting end of the agitator shaft 14 whereupon the agitator shaft may be oscillated back and forth independently of the power mechanism.

15 From the foregoing, it is obvious that I have provided a driving mechanism for a washing machine that is simple and inexpensive to construct, and which is readily connected with and disconnected from the agitating mechanism of the machine.

20 What I claim and desire to secure by Letters Patent is:

25 1. An apparatus for operably connecting the agitator of a washer with a prime mover including a transmission housing, a pinion in the housing having connection with the agitator, a reciprocating member meshing with the pinion, means for slidably retaining the reciprocating member 30 in constant meshing relation with the pinion, a crank shaft rotatably mounted in the housing, means for connecting a prime mover with the crank shaft, a pitman on the crank shaft having a latch shaped head for latchingly engaging the reciprocating member, and means for guidingly retaining the latch shaped head of the pitman in engagement with the reciprocating member including means for moving the pitman to and from latched engagement with said reciprocating 35 member.

40 2. An apparatus for operably connecting the agitator of a washer with a prime mover including a transmission housing, a pinion in the housing having connection with the agitator, a reciprocating member meshing with the pinion, means for slidably retaining the reciprocating member 45 in constant meshing relation with the pinion, a crank shaft rotatably mounted in the housing, means for connecting the prime mover with the crank shaft, a pitman on the crank shaft having a latch shaped head for latchingly engaging the reciprocating member and a guide groove extending longitudinally of the pitman, a lever arm pivotally mounted in the housing, a guide pin on

the arm engaging in said groove of the pitman, a pin on the reciprocating member, and means for actuating the lever arm to cause the guide pin to move the latch shaped head of the pitman into and out of engagement with said pin on the reciprocating member.

45 3. An apparatus for operably connecting the agitator of a washer with a prime mover including a transmission housing, a pinion in the housing having connection with the agitator, a reciprocating member meshing with the pinion, means for slidably retaining the reciprocating member 50 in constant meshing relation with the pinion, a crank shaft rotatably mounted in the housing, means for connecting the prime mover with the crank shaft, a pitman on the crank shaft having a latch shaped head for latchingly engaging the reciprocating member and a guide groove extending longitudinally of the pitman, a lever arm pivotally mounted in the housing, a guide pin on the arm engaging in said groove of the pitman, a pin on the reciprocating member, means for actuating the lever arm to cause the guide pin to move the latch shaped head of the pitman into and out of engagement with said pin on the reciprocating member, and means yieldingly retaining said lever arm in said selected position.

55 4. In an apparatus of the character described, a housing, a pinion rotatably mounted in the housing, a rack meshing with the pinion, means 60 for slidably retaining the rack in constant meshing relation with the pinion, a driving member in the housing, a pitman on the driving member having a latch shaped head for latchingly engaging the rack, and means for guidingly retaining the pitman in latched engagement with the rack including means for moving the pitman from latched engagement with the rack.

65 5. In an apparatus of the character described, a housing, a pinion rotatably mounted in the housing, a rack meshing with the pinion, means 70 for slidably retaining the rack in constant meshing relation with the pinion, a driving member in the housing, a pitman connected with the driving member and having a latch shaped head and a 75 guide groove extending longitudinally of the pitman, a lever arm pivotally mounted in the housing, a guide on the lever arm engaging in said groove of the pitman, latch engaging means on the rack, and means for actuating said lever arm to cause the guide to move the latch shaped head of the pitman into and out of engagement with the latch engaging means on the rack.

LEWIS A. JAMES.
